(57) **CLAIM**

The ornamental design for an electronic display for a wearable device with graphical user interface, as shown and described.

DESCRIPTION

The file of this patent contains at least one drawing executed in color. Copies of this patent with color drawing(s) will be provided by the Office upon request and payment of the necessary fee.

FIG. 1 is a front view of an electronic display for a wearable device with graphical user interface, showing our new design;

FIG. 2 is an enlarged front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line showing of the wearable device in FIGS. 1, 3-7 forms no part of the claimed design. The broken line showing of the hour and minute hands, and the text in FIGS. 1 and 2, forms no part of the claimed design.
